UNITED STATES PATENT OFFICE.

SAMUEL FRANKLIN ABERNATHY, OF ROANOKE, ALABAMA.

PIPE CLEANER.

Application filed June 1, 1925. Serial No. 34,154.

To all whom it may concern:

Be it known that I, SAMUEL FRANKLIN ABERNATHY, a citizen of the United States, residing at Roanoke, in the county of Randolph and State of Alabama, have invented a new and useful Pipe Cleaner, of which the following is a specification.

This invention relates to cleaners for sewer and other pipes and the object thereof 10 is to provide a simple and efficient device of this character for cutting out roots in sewers and removing other obstructions.

Another object is to provide a device of this character which may be pushed from 15 the man hole in a sewer through the pipe until it comes to the next man hole at which point the device with the obstructions may be removed.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

30 In the accompanying drawings:—

Figure 1 represents a side elevation of 35 a pipe cleaner constructed in accordance with this invention;

Figure 2 is a longitudinal section thereof; 40 Figure 3 is a transverse section taken on the line 3—3 of Figure 2.

In the embodiment illustrated a handle member 1 is shown which is preferably made 45 tubular in form for lightness and to the outer end of which is designed to be secured a pipe, not shown for pushing the device through a sewer.

Metal straps 2 and 3 are secured at one end to the handle 1 at diametrically opposite sides and project beyond said end, the 45 projecting portions diverging as shown at 4 for a portion of their length and then extending forwardly parallel with each other as shown at 5,

Metal bands 6 and 7 are secured to the 50 members 5 at longitudinally spaced points and are designed as supports for the obstruction removing scoop members 8 and 9 which are semi-cylindrical or arcuate in cross section and are riveted to the bands 6 and 7. 55 The member 8 terminates short of the member 9 and the outer ends of both of said members are flared and sharpened to provide cutting lips 10.

By forming the cutting members 8 and 9 of different lengths and arranging them at diametrically opposite points one of said members will cut roots during the passing of the device through the pipe at one point and the other at another point thereby ensuring 60 cutting and pushing forward of all roots.

This device while primarily intended for cutting roots in sewers may also be used for dragging chunks of paper and other obstructions through the sewer and delivering them 70 at the man hole.

I claim:—

1. A pipe cleaner comprising a handle member having diverging arms secured thereto, said arms merging at their front ends into parallel arms, annular bands connecting said arms in longitudinally spaced relation, and cleaning blades carried by said bands and spaced peripherally from each other, one of said blades being longer than 80 the other.

2. A pipe cleaner comprising a handle member having diverging arms secured thereto, said arms merging at their front ends into parallel arms, annular bands connecting said arms in longitudinally spaced relation, and cleaning blades carried by said bands and spaced peripherally from each other, one of said blades being longer than 85 the other, the front ends of said blades being flared and provided with sharp lips.

In testimony that I claim the foregoing as my own, I have hereto affixed my signature.

SAM FRANK ABERNATHY.
